(57) **CLAIM**

I claim the ornamental design for a four column garment dryer, as shown and described.

DESCRIPTION

FIG. 1 is a rear perspective view of the four column garment dryer invention;

FIG. 2 is a front perspective view of the four column garment dryer;

FIG. 3 is a front perspective view of the four column garment dryer with lines showing possible attachments thereon;

FIG. 4 is a rear elevation view thereof;

FIG. 5 is a top view thereof;

FIG. 6 is a front elevation view thereof;

FIG. 7 is a first side elevation view thereof;

FIG. 8 is a second side elevation view thereof; and,

FIG. 9 is a bottom view thereof.

The broken line showing of the four column garment dryer is included for the purpose of illustrating environmental matter and forms no part of the claimed design.
